UNITED STATES PATENT OFFICE.

FRED C. DICKOW, OF CHICAGO, ILLINOIS.

INDEX-CENTER OR THE LIKE.

1,383,698.

Specification of Letters Patent. Patented July 5, 1921.

Application filed December 31, 1917. Serial No. 209,635.

To all whom it may concern:

Be it known that I, FRED C. DICKOW, a citizen of the United States, residing at Chicago, in the county of Cook and State 5 of Illinois, have invented certain new and useful Improvements in Index-Centers or the like, of which the following is a description.

My invention belongs to that general class 10 of devices known as index centers, dividing engines or rotary tables which are used in connection with milling machines or the like. The invention has among its objects the production of an improved index center 15 of the kind described that is simple, convenient, compact, durable, efficient and satisfactory for use wherever found applicable. More particularly it has among its objects the production of an index center 20 provided with means for positively locking the spindle, and which locking means will hold the spindle perfectly central in line and not in any way tend to force the same out of line. It has as a further object the 25 production of a device in which the spindle actuating mechanism may be conveniently operated or controlled in setting the device. Many other objects, uses and advantages of the construction herein shown will be obvious 30 to those skilled in the art from the disclosure herein made.

To this end my invention consists in the novel construction, arrangement and combination of parts herein shown and described, and more particularly pointed out 35 in the claims.

In the drawings, wherein like reference characters indicate like or corresponding parts,

40 Figure 1 is a front elevation of the complete index center;

Fig. 2 is a side elevation of the same;

Fig. 3 is a sectional view taken substantially on line 3—3 of Fig. 2;

45 Fig. 4 is a sectional view taken substantially on line 4—4 of Fig. 3; and

Fig. 5 is a perspective view of the spindle locking member.

Referring to the drawings, 1 represents a 50 base or frame which may be mounted and secured on the milling machine table in any desired manner, and which is arranged to carry the swivel block 2, which carries a tubular spindle 3. The spindle center 4 is

carried by the spindle 3 in the usual manner. As shown, the swivel block 2 is mounted and secured on the front clamping member 5 and the clamping member 6, the same being movable or adjustable thereon. In the construction shown the same is secured to 60 the part 6 by the clamping plate 7, bolts 8 and suitable nuts. The same may be clamped or secured to the front clamp member 5 by a clamp member 9 and controlling member 10 therefor. The particular 65 method or means of securing the swivel block on the base of frame 1, however, forms no part of the present invention, consequently need not be described in further detail.

70 Arranged on the spindle 3 is a worm wheel 14 which meshes with the worm 15 arranged in the worm case 12, and which is carried on and operated by a shaft 16 provided with a crank arm 17. An index 75 plate 18 is provided as shown, having the desired number of holes 19 arranged to cooperate with the pin 20 carried at the end of the crank arm. Without describing the crank construction in detail at this time, it 80 may be mentioned that 21 is the crank handle provided with an extending handle part 22, by means of which the pin 20 may be controlled and pulled out of or pushed into engagement with the index plate 18 at any one 85 of the holes 19. No attempt has been made to show the location of the holes accurately. Turning shaft 16 by means of the crank arm 17 rotates the worm 15 and through it turns the worm wheel 14, which is secured 90 on the spindle, thereby turning or rotating the spindle.

95 In a device of this kind it is necessary or desirable to positively lock the spindle in the desired set position. The locking means should be positive, however, and so that the same may be quickly and easily locked or unlocked. In locking the spindle, however, the locking or securing should be in such a manner that the spindle carrying the 100 center will not be forced out of line or be deflected. Referring particularly to Figs. 3, 4 and 5, I mount a clamping member 24 on the spindle, the same being substantially in the form of a split ring with the extending parts 25 and 26 at each side of the split 24. A spring 28 carried by the pin 27 tends to normally force the extensions 25 and 26

apart and cause the clutch or ring 24 to release the spindle. Referring particularly to Fig. 4, it will be noted that the part 26 abuts against a shoulder 29 on the base 1, 5 while the part 25 abuts against a similar shoulder 30 on the base. The clutch is controlled by a bolt of clutch controlling member 31, preferably provided with a handle 32 so that a wrench is not necessary in operating the clutch. In the construction 10 shown, the member 31 is in threaded engagement with the sleeve 33 which is threaded in an opening provided for it. Obviously when member 31 is screwed in it tends to 15 force part 25 toward part 26, causing the clamp or clutch 24 to firmly grip the spindle and lock it against movement. Turning the member 31 in the opposite direction or out releases the clutch and the spring 20 28 assists the spring in the clutch ring to return the clutch to its disengaged position. It will be particularly noted that with this construction the spindle is grasped substantially completely about the same without 25 any tendency to force the same out of line or deflect it; on the contrary, if anything it tends to hold it in line.

The crank arm 17 is so arranged on the shaft 16 that it may be easily removed and 30 slipped or adjusted. Referring to the figure, the arm 17 is provided with the slot 35 with an enlarged part 36 at the end, so that the nut on the shaft 16 need only be loosened and not be entirely removed. A sleeve 37 is 35 carried at the end of the arm and normally locked in position by the clamping screw 38, the crank being slotted to form a clamp. Sleeve 37 carries a micrometer screw, as it may be termed, 39, 40 being the handle by 40 which the same may be turned. The shoulder on the inner end of the sleeve, and the handle 40 prevents the sleeve being removed or from accidentally being lost, as the screw 39 must be first entirely removed to remove 45 the sleeve. In adjusting the crank so that the pin 20 will engage any particular row of holes, the nut on the end of shaft 16 is loosened and the screw 39, which bears against the shaft, is turned to the desired 50 extent to bring pin 20 to the desired hole or opening 19. The sleeve 37 may be adjusted by adjusting the screw 38. It is therefore a comparatively simple matter to bring the pin 20 to register with any hole. By the 55 term "index center" in the claims, I wish to be understood as including index centers, dividing engines, dividing heads, circular head and dividing engines, rotary milling tables or the like, in which it may be desired to lock a spindle or center.

Having thus described my invention, it is obvious that various immaterial modifications may be made in the same without departing from the spirit of my invention, 60 hence I do not wish to be understood as

limiting myself to the exact form, construction, arrangement and combination of parts herein shown and described or uses mentioned.

What I claim as new and desire to secure 70 by Letters Patent is:—

1. In a spindle locking device for index centers, and in combination a support, a work holding spindle mounted on said support, the support having bearings for the 75 spindle adjacent its ends, and means for locking the spindle against movement relatively to the support, said means comprising a split ring clutch member arranged on the spindle to engage the same intermediate said bearings, and means for controlling the split ring clutch whereby the spindle is locked against movement relatively to the support. 80

2. In a spindle locking device for index 85 centers, a spindle, a supporting block for the spindle, said block being provided with an interior chamber and an opening extending from said chamber to the front face of the block, and means operable from the front face of the block for securing the spindle against movement relative to the block, said means comprising a clutch located wholly within the chamber of the block, and an operating stem member for the clutch having an adjustable threaded engagement with the 90 supporting block, said member extending through the opening in the supporting block to the outer face thereof. 95

3. In a device of the class described, a spindle, a supporting block for the spindle, 100 said block being provided with an interior chamber, and an opening in the block extending from said chamber to the exterior of the block, and an abutment wall located interiorly of the block adjacent said chamber, and means for securing the spindle against movement relatively to the block comprising a split ring clutch part provided with a radial extension to coöperate with 105 said abutment wall, the clutch part and extension being located wholly within the chamber of the block, and an operating member for the split ring clutch part extending through the opening in the supporting block and having its inner end operatively associated with the split-ring clutch part. 110

4. In a device of the class described, a spindle, a supporting block for the spindle, 115 said block being provided with an interior chamber and an opening in the block extending from said chamber to the exterior of the block, and an abutment wall located interiorly of the block adjacent said chamber, and means for securing the spindle against movement relatively to the block, comprising 120 a split-ring clutch part provided with radial extensions adjacent its free end portions, the clutch member and extension being located wholly within the chamber of the block, one of said radial extensions being adapted to 125 130

coöperate with said abutment wall, and an operating stem member for the split ring clutch part having an adjustable threaded engagement with the supporting block, said 5 stem member extending through the opening in the supporting block and adapted at its inner end to engage the other radial extension of the split-ring clutch part.

In testimony whereof, I have hereunto signed my name in the presence of two sub- 10 scribing witnesses.

FRED C. DICKOW.
